[57] CLAIM

The ornamental design for a multiple bin refuse container, as shown and described.

DESCRIPTION

FIG. 1 is a perspective view of a multiple bin refuse container showing our new design, with the lid partially opened to expose two partitions at optional bin defining positions;

FIG. 2 is a front view thereof, with lid fully opened; FIG. 3 is a front view thereof, with lid closed, the opposite side being substantially identical;

FIG. 4 is a side view thereof with lid open;

FIG. 5 is a side view thereof with lid closed;

FIG. 6 is a top view thereof, with lid removed;

FIG. 7 is a top view thereof, with lid closed;

FIG. 8 is a rear view thereof;

FIG. 9 is a bottom view thereof; and,

FIG. 10 is a perspective view of a partition depicted in FIG. 1, showing one major surface of the partition, the opposite major surface thereof being identical.

FIG. 6

FIG. 7

FIG. 5

FIG. 8

FIG. 9

FIG. 10
